Primary Examiner — Sandra S Snapp*Assistant Examiner* — Mehri F Bajoul(74) *Attorney, Agent, or Firm* — Thomas A. O'Rourke; Bodner & O'Rourke, LLP(57) **CLAIM**

The ornamental design for a disk, as shown and described.

DESCRIPTION

FIG. 1 is a front perspective view of a disk showing the new design;

FIG. 2 is top view thereof;

FIG. 3 is a bottom view thereof; and,

FIG. 4 is a side view of the disk thereof, taken along line 4-4 within FIG. 2. The views of the disk rotated 60 or 120 degrees from FIG. 4 are identical.

The broken lines in FIG. 3 depict portions of the disk that form no part of the claimed design.
